A. S. Patterson,
ATTORNEY

UNITED STATES PATENT OFFICE.

JOSEPH BECK, OF TWO HARBORS, MINNESOTA.

FURNACE-GRATE.

1,090,014.

Specification of Letters Patent. Patented Mar. 10, 1914.

Application filed February 20, 1911. Serial No. 609,795.

To all whom it may concern:

Be it known that I, JOSEPH BECK, a citizen of the United States, residing at Two Harbors, in the county of Lake and State of Minnesota, have invented certain new and useful Improvements in Furnace-Grates, of which the following is a specification, reference being had therein to the accompanying drawing.

10 My invention relates to improvements in furnace grates, and pertains more particularly to grates used in corrugated furnaces.

The object of my invention is to provide a grate for a furnace of this character in 15 which a larger grate area is obtained without altering the dimensions of the furnace and thus increasing the efficiency of the boiler.

Another object of my invention is to provide 20 a more simple, cheap and effective grate having certain details of structure hereinafter set forth in the specification.

In the accompanying drawings Figure 1 is a horizontal sectional view, partly broken 25 away, of a corrugated furnace equipped with my improved grate bar. Fig. 2 is an enlarged side elevation of a portion of a grate showing a modified form. Fig. 3 is an enlarged side elevation of Fig. 2, showing the 30 furnace in section.

Referring now to the drawings, 1 represents the walls of a corrugated furnace, such as are in common use, and 2 represents the grate bars that are usually used in 35 simple furnaces of this character. The side-bars 3 of my improved grate are very similar to the intermediate bars 2, except that they have removably secured thereto the laterally extending stub-bars 4, extending 40 within the convex corrugations of the furnace walls 1, thus providing much more grate surface without increasing the size of the furnace or boiler, as will be readily seen.

The side-bars adjacent their lower ends are 45 provided with laterally extending projections 6, upon which the removable plate 5 rests, and said plate resting flat against the side of the side-bars 3 and secured thereon in any desired manner. The lateral stubs 4

in this form are formed integral with the 50 plate 5, and extend out and engage the side-walls 1 of the boiler. The lower extremity of the plate 5 is provided with a suitable foot 7 which rests upon the upper face of the laterally extending projections 6, whereby 55 the weight of the plate 5 and its load is supported by the projections 6''. The upper edge of the plate 5 is beveled or slanting as indicated at 8 to prevent ashes and the like resting upon the upper edge. It is 60 evident that this device is applicable to various forms of either stationary or shaking grates.

Having thus described my invention, what I claim and desire to secure by Letters Patent is:

1. A grate for corrugated furnaces, the side bars of the grate having laterally extending projections at their lower faces spaced apart, plates having a beveled 70 upper edge and laterally extending spaced grate fingers adapted to project within corrugations of the furnace, said plates resting against the side bars and having tapering lower ends terminating in reduced laterally 75 extending projections resting upon the projections of the side bars and extending beyond the same and means for securing said plates to the side bars.

2. A grate for corrugated furnaces, the side bars of the grate having laterally extending projections at their lower sides spaced apart and gradually tapering in width, plates having laterally extending spaced grate fingers adapted to extend 85 within the corrugations of the furnace, said plates resting against the side bars and having tapering lower ends terminating in lateral projections gradually tapering in width and resting upon the projections of the 90 side bars, and means for securing the plates to the side bars.

3. A grate for corrugated furnaces, the side bars of the grate having lateral projections at their lower sides spaced apart and 95 gradually tapering in width, plates having lateral spaced grate fingers adapted to extend within the corrugations of the furnace

and of different lengths, said plates resting against the sides of the side bars and having a tapering lower end terminating in laterally extending projections gradually tapering in width and resting upon the projections of the side bars, and means for securing the plates to the side bars.

In testimony whereof I hereunto affix my signature in the presence of two witnesses.

JOSEPH BECK.
